Primary Examiner — Robin V Webster(74) *Attorney, Agent, or Firm* — P. Jeff Martin; The Law Firm of P. Jeff Martin, LLC**CLAIM**

The ornamental design for a cloth with magnet, as shown and described.

DESCRIPTION

FIG. 1 is a top perspective view of a cloth with magnet showing my new design;

FIG. 2 is a right side view thereof;

FIG. 3 is a left side view thereof;

FIG. 4 is a front end view thereof;

FIG. 5 is a rear end view of thereof;

FIG. 6 is a top plan view thereof; and,

FIG. 7 is a bottom plan view thereof.

The pattern which is partially shown for ease of illustration represents the fabric texture and appearance and is understood to repeat uniformly throughout the indicated area. The lighter weight dashed lines featured on the article represent a stitching line.
